CLAIM

The ornamental design for a wall mountable bathing pillow, as shown and described.

DESCRIPTION

FIG. 1 is a left, frontal, top perspective view of a wall mountable bathing pillow showing our new design;

FIG. 2 is a front elevational view thereof;

FIG. 3 is a top plan view thereof;

FIG. 4 is a bottom plan view thereof;

FIG. 5 is a right side elevational view thereof, the left side elevational view being a mirror image thereof;

FIG. 6 is a left, frontal, top perspective view of a second embodiment;

FIG. 7 is a front elevational view thereof;

FIG. 8 is a top plan view thereof;

FIG. 9 is a bottom plan view thereof; and,

FIG. 10 is a right side elevational view thereof, the left side elevational view being a mirror image thereof.

The fragmentary broken line representations of a bathing fixture in FIGS. 1 and 6 are for purposes of illustration only and forms no part of the claimed design.

1 Claim, 4 Drawing Sheets
